UNITED STATES PATENT OFFICE.

PHILIP LANGE, OF PITTSBURG, PENNSYLVANIA, ASSIGNOR TO THE WESTINGHOUSE ELECTRIC COMPANY, OF SAME PLACE.

SWITCH FOR ELECTRIC CIRCUITS.

SPECIFICATION forming part of Letters Patent No. 434,152, dated August 12, 1890.

Application filed September 1, 1887. Serial No. 248,483. (No model.) Patented in England May 29, 1888, No. 7,851; in Belgium May 29, 1888, No. 81,966; in Italy May 29, 1888, XXII, 23,538, and XLVI, 259, and in France May 29, 1888, No. 190,873.

To all whom it may concern:

Be it known that I, PHILIP LANGE, a citizen of the United States, residing in Pittsburgh, in the county of Allegheny and State 5 of Pennsylvania, have invented certain new and useful Improvements in Switches for Dynamo-Electric Machines, (for which I have obtained Letters Patent in Great Britain, No. 7,851, dated May 29, 1888; in Italy, No. XXII, 10 23,538, and XLVI, 259, dated May 29, 1888; in France, No. 190,873, dated May 29, 1888, and in Belgium, No. 81,966, dated May 29, 1888,) of which the following is a specification.

The invention relates to the construction 15 of switches for controlling the circuit-connections of dynamo-electric generators delivering currents of high potential.

The object of the invention is to provide 20 convenient and reliable means for securing the connections without danger to the operator, and in such manner that the apparatus will not be injured by the sparks formed upon completing and interrupting the connections.

25 The invention will be described in connection with the accompanying drawings, which show the switch in connection with a safety device, Figure 1 being a plan, and Fig. 2 a side view.

30 Referring to the figures, A represents a base of non-conducting material, such as wood. There are two switches shown, one being employed for each pole of the generator. One only, however, need be described in detail. A conductor L is fastened to a binding-plate a', secured to the base A. This plate is provided with a fusible stripe c', which connects it with a second plate b'. This plate b' may be connected, by means of a suitable 35 switch-plug, with a binding-plate e'. This plate e' in turn is connected by a conductor f with a spring contact-plate k'. A second contact-plate k² is employed for receiving a conductor L' passing to the apparatus to be supplied with currents. This second plate is 40 upon the opposite side of the switch from the

plate k', thus separating the conductor L' from the conductor f as far as practicable.

A lever K is employed for connecting the two spring-plates with each other when desired. This lever is pivoted at n and is provided with a handle n' of non-conducting material. The lever is formed with a blade or knife edge k, which passes between the respective springs j' j' and j² j², thus forming 55 good connections. The movement of the lever may be sudden, and thus form the connections quickly. The blade k is preferably widened toward its outer end, so as to make contact with both sets of springs at about 60 the same time. The base is preferably fastened in a vertical position, so that when the switch is closed the handle n' is toward the wall and projecting downward. By simply throwing the handle outward the switch will 65 be opened. This is of great service in that it renders it very easy to determine the condition of the several switches of a group at a glance.

As it frequently chances in connecting generators together, or from other causes—such as the formation of short circuits—the safety-strip c' may be burned out, it is desired to provide, in connection with the switch, a second safety-strip c². This connects the plate 70 e' with a plate a². The plate a² may be electrically connected with the plate a' by a switch-plug in case the safety-strip c' is burned out. This affords a ready method of substituting a new fusible strip without 75 delaying the operation of the machines. For the purpose of holding the lever K in either of its two positions a spring s is placed in the socket N. This serves to press a rounded pin t against the squared end of the lever K, 80 and it prevents accidental displacement.

I claim as my invention—

A switch for controlling electric-circuit connections, consisting of a pivoted lever moving in a plane perpendicular to the base, an 85 insulated support therefor, two contact-plates constituting the respective terminals of an 90

electric circuit, a plate carried by the lever, widening gradually from the pivot of the lever toward the contact-plate most distant from the point of support of the lever, and 5 binding-plates for securing electrical connection with the respective contact-plates located upon opposite sides of the lever, substantially as described.

In testimony whereof I have hereunto subscribed my name this 5th day of May, A. D. 1887.

PHILIP LANGE.
